UNIVERSAL MOUNTING ANTENNA CLAMP

Marvin J. Blaugrund, Shaker Heights, Ohio

Application April 1, 1949, Serial No. 84,965

9 Claims. (Cl. 248—43)

1

This invention relates generally to mounting devices adapted to secure antenna in position and more particularly to a mounting device for video antennae which is so designed and constructed as to be universally adjustable.

In installing antennae for video receivers and the like, it is oftentimes necessary to mount the antennae on sloping surfaces, on vertical surfaces, on the corners of buildings or chimneys, and beneath overhanging eaves. The particular location of the antennae is dictated by several factors, the primary consideration being the desirability of obtaining optimum reception.

Most antennae are provided with a mounting plate at the base thereof, and this plate may be pivotally secured to the antennae so as to permit some angular adjustment thereof. However, it is my experience that such mounting plates are in far too many instances inadequate to permit proper installation of the antennae. When faced with an awkward installation problem, the installer must contrive a suitable mounting using odd pieces of lumber and the like, which result in an unsightly and, often, flimsy antennae installation.

It is a primary object of my invention to provide an antenna mounting which, by suitable arrangement of the parts thereof, can be adjusted to any and all positions desired relatively to the antennae.

Another object of my invention is to provide an antennae clamp of the character described, which is adaptable to installation on vertical and inclined surfaces of the type heretofore mentioned, as well as on chimney corners.

Still another object of my invention is to provide an antennae clamp which consists of a few relatively inexpensive easily manufactured parts, which is nonetheless sturdily constructed and well adapted for its intended use.

Other objects and advantages of the invention will be apparent during the course of the following description.

In the accompanying drawings, forming a part of this specification, and in which like numerals are employed to designate like parts throughout the same,

Fig. 1 is an elevation view of an antennae clamp embodying the features of my invention as it appears when mounted on a window ledge or the like, beneath an overhang.

Fig. 2 is another view in elevation showing the antennae clamp mounted on an inclined surface.

Fig. 3 is a top plan view of the antennae clamp mounted on a horizontal surface.

2

Fig. 4 is a top plan view of the antenna clamp secured to a chimney or building corner.

Fig. 5 is a cross sectional view taken on line 5—5 of Fig. 2, the screws not being shown.

Fig. 6 is a fragmentary cross-sectional view taken on line 6—6 of Fig. 5.

Fig. 7 is a fragmentary cross-sectional view taken on line 7—7 of Fig. 6.

Referring more particularly to the drawings, 10 the antennae clamp comprises four major components, a base plate 1, a triangular brace 2, a clamp bar 3, and a clamp bar extension 4.

The plate 1 is a rectangular metal piece, two ends of which are bent inwardly at 180° to form 15 retainers 5 which overlie the body of the plate 1 and are spaced vertically therefrom. Longitudinal slots 6 are formed in the plate 1 at the ends thereof and when the ends have been bent back upon themselves in the manner heretofore described, each slot 6 defines an aperture which extends through the retainer 5 and body of the plate 1.

The plate 1 is also provided with a plurality of spaced openings 7 which, as will more fully appear hereinafter, are utilized in securing the plate 20 to the surfaces on which it is mounted.

The brace 2 has two integral leg portions 8 which extend at right angles to each other from their juncture point or apex 9. The end of each leg portion 8 is bent 45° to form a flange portion 10 which is slotted as at 11.

The flanges 10 are slidable into the space between the body of plate 1 and the retainers 5 so that the brace 2 may be readily assembled 25 with the base plate 1 or may be quickly disassembled therefrom. When thus assembled, the slots 11 in the flanges 10 intersect or traverse the slots 6 in the base plate 1 so as to permit fastening means, such as screws 12, to be passed there-through.

The legs 8 are also provided with spaced openings 13 for a purpose to be hereinafter described.

At the juncture 9 of the legs 8 is secured, as by welding, a clamping sleeve 14 having an open-sided cylindrical body portion 15 and substantially parallel ear portions 16 which project outwardly from the body 15. The ears 16 are provided with aligned openings which permit bolts 17 to be passed through the ears and be retained thereon by nuts 18. The nut and bolt can be manipulated to draw the ears 16 toward each other and thus to constrict the sleeve 14 and cause it to frictionally grip or clamp a cylindrical member lying therein. The sleeve body 15 has sufficient 35 inherent resiliency to expand or return to its

initial size when the tension effected by the bolts 17 and nuts 18 is relieved.

The clamping sleeve 14 is adapted to receive either the clamp bar 3 or the clamp bar extension 4, interchangeably, the only distinction between the members being that the extension 4 is of greater overall length than the bar 3. Depending upon the particular conditions encountered in the installation of the antennae, one or the other of these members may be secured to the brace 2, as will be more fully described hereinafter.

The clamp bar 3 consists of a short length of tubing forming a body 19 to one end of which is secured as by welding a clamping sleeve 20, identical in all respects to the clamping sleeve 14 previously described. The sleeve 20 is so mounted that its longitudinal axis is normal to the longitudinal axis of the tubular body 19.

The clamp bar extension 4 consists of a length of tubing forming a body 21 which is longer than the body 19 of the bar 3. To one end of the body 21 is secured, as by welding, a clamping sleeve 22 which is identical in all respects to the sleeves 14 and 20. The sleeve 22 is mounted so that its longitudinal axis is normal to the axis of the tubular body 21.

In order to satisfactorily accommodate antennae shafts which may be of smaller diameter than is customarily encountered, I also provide an adapter 23 which is shown in Fig. 3. The adapter is an open-sided cylindrical sleeve which has an external diameter of slightly smaller dimension than the internal diameter of the clamping sleeves 20 or 22. It nests loosely in either of the clamping sleeves and is constricted in response to constricting movement of the sleeve body 15.

I will now describe the manner of use of my universal mounting antennae clamp.

In Fig. 1 I have illustrated an antennae installation on a dormer ledge in which it is necessary that the antennae T be located far enough away from the ledge to clear the overhang. In utilizing the antenna clamp, the base plate 1 is first secured to the ledge by the screws 12, the plate extending longitudinally in a direction corresponding to the width of the ledge.

The brace 2 is then assembled to the plate 1, the retainers 5 thus overlying the flanges 10 of the brace. Screws 12 are then passed through the slots 6 and 11 and serve to secure the assembled components to the ledge.

As it is desired to locate the antennae T away from the wall, the long clamp extension bar 4 is placed in the clamping sleeve 14 of the brace 2 and secured therein by tightening the screws 17, the bar 4 being first rotated so that the axis of the clamping sleeve 22 is horizontal. The clamping bar 3 is then placed in the clamping sleeve 22 and is rotated until the axis of the clamping sleeve 20 is vertical. The clamping sleeve 22 is then constricted by means of the screws 17 to grip the body 19 of the bar 3. The antennae T can then be positioned vertically in the clamping sleeve 20 and secured by tightening the screws 17.

In Fig. 2 I have illustrated an antennae installation involving the same conditions as those shown in Fig. 1, except that in this instance, the surface on which the base plate 1 is mounted is not of sufficient width to permit a laterally extending mounting. It is therefore required that the plate 1 and the brace 2 be mounted in the manner shown, the axis of the clamping

sleeve 14 being parallel to the mounting surface.

The clamping bar 3 is now secured to the brace 2 with the axis of the clamping sleeve 20 lying in a horizontal plane, but normal to the axis of the sleeve 14.

The extension bar 4 is then secured to the bar 3 with the axis of its clamping sleeve 22 extending vertically, permitting the antennae to be secured thereto.

In Fig. 3 I have illustrated the manner of mounting on a horizontal surface, the assemblage of parts being the same as those of the mounting shown in Fig. 2. It will be apparent, that this same assemblage of parts is easily adaptable to an installation on a vertical surface, it being necessary only to rotate the clamping bar 3 to a position 90° removed from that shown in Fig. 3.

In Fig. 4 I have illustrated a very practical application of my universal mounting antennae clamp which evidences its adaptability to various conditions encountered by installers. In this instance, a chimney has been selected as the best place for mounting the antennae. In this installation, the base plate 1 is not used, the brace 2 being secured directly to the corner of the chimney by the screws 12 which pass through the openings 13 provided in the legs 8 of the brace.

If additional security of mounting is desired, a strap S may be looped through the slots 11 in the flanges 10 of the brace 2 and drawn tightly in encirclement about the chimney. In some instances it is necessary to use only the screws 12 to secure the brace 2 to the chimney, however, in other cases, it is not feasible to use the screws and reliance must be had solely on the strap.

This form of mounting may obviously be utilized with equal facility on the corner of a building or the like.

The antennae may, in this instance, be secured directly in the clamping sleeve 14, or if preferred, any combination of one or both of the bars 3 and 4 may be used in the manner heretofore described with reference to Figs. 1, 2 and 3.

From the foregoing description, it will be apparent that my invention possesses great versatility in being adaptable to a great variety of antennae installations. It will be noted that the clamp bar 3 and the extension bar 4 are each rotatable about their own longitudinal axes as well as being slidably longitudinally in the clamping sleeves in which they are to be secured. Thus the antenna clamp is adjustable both for length and for direction.

It will also be noted that my universal mounting antennae clamp consists of a relatively few inexpensive easily manufactured parts which lend themselves readily to quantity production. In this connection, it will be apparent that the clamp I have described need not be made exactly in the manner illustrated. For example, it is entirely feasible to make the brace 2 out of two pieces, each forming one leg 8 and one-half portion of the clamping sleeve 14, the legs being suitably joined or secured at the apex point 9 as by screws or welding. Other manufacturing economies of a similar nature may likewise suggest themselves to those skilled in the art.

It is to be understood that the form of my invention, herewith shown and described, is to be taken as a preferred example of the same, and that various changes in the shape, size and arrangement of parts may be resorted to, without

departing from the spirit of my invention, or the scope of the subjoined claims.

Having thus described my invention, I claim:

1. A mounting clamp for antennae or the like, comprising a member adapted for attachment to a mounting surface, a clamping sleeve provided on said member, a clamping bar rotatably mounted in said clamping sleeve and axially slidably therein, and a clamping sleeve integrated with said clamping bar, said second-named clamping sleeve being disposed in a position normal to the position of said first-named clamping sleeve.

2. A mounting clamp for antennae or the like, comprising a member adapted for attachment to a mounting surface, a clamping sleeve provided on said member, a clamping bar receivable in said clamping sleeve and secureable therein, said clamping bar being axially slidable and rotatable in said clamping sleeve prior to the clamping thereof, and a second clamping sleeve integrated with said clamping bar for frictionally gripping an antennae mast, said second clamping sleeve having a longitudinal axis which lies normal to the longitudinal axis of said first-named clamping sleeve.

3. A mounting clamp for antennae or the like, comprising a member adapted for attachment to a mounting surface, a clamping sleeve on said member, a clamping bar rotatably mounted in said clamping sleeve, and axially slidable therein, a second clamping sleeve provided on said clamping bar, a clamping bar extension rotatably mounted in said second clamping sleeve and axially slidable therein, and a third clamping sleeve provided on said clamp bar extension for frictionally gripping an antennae mast.

4. A mounting clamp for antennae or the like, comprising a member adapted for attachment to a mounting surface, a clamping sleeve provided on said member, a clamping bar rotatably mounted in said clamping sleeve and axially movable therein, a second clamping sleeve provided on said clamping bar, a clamping bar extension rotatably mounted in said second clamping sleeve and axially movable therein, and a third clamping sleeve provided on said clamping bar extension, said second clamping sleeve having its longitudinal axis disposed in a position normal to the longitudinal axis of said first-named clamping sleeve, and said third clamping sleeve having its longitudinal axis disposed in a position normal to the longitudinal axis of said second clamping sleeve.

5. A mounting clamp for antennae or the like, comprising a brace member having two leg portions disposed angularly each to the other, said leg portions having a common juncture point, an outwardly extending flange provided on the terminus of each of said leg portions in co-planar relationship each to the other, said flanges being apertured to permit the passage of securing means therethrough, and a clamping sleeve pro-

vided at said juncture point of said brace member for frictionally gripping an antennae mast.

6. A mounting clamp for antennae or the like, comprising a brace member having two leg portions disposed angularly each to the other, a flange provided on the terminus of each of said leg portions in coplanar relationship, a clamping sleeve surmounting said leg portions, and a base plate adapted for attachment to a mounting surface, said base plate having retainer portions formed thereon which overlie said flanges when said brace member is assembled with said base plate.

7. A mounting clamp, as defined in claim 6, in which said flanges are provided with apertures which are aligned with apertures in said base plate to permit the passage of securing means therethrough.

8. A mounting clamp for antennae or the like, comprising a brace member having two leg portions disposed angularly each to the other, a flange provided on the terminus of each of said leg portions in coplanar relationship, a clamping sleeve surmounting said leg portions, a clamp bar receivable in said clamping sleeve, and a second clamping sleeve provided on said clamp bar, said second clamping sleeve having its longitudinal axis disposed in a plane normal to the longitudinal axis of said first-named clamping sleeve.

9. A mounting clamp for antennae or the like, comprising a brace member having two leg portions disposed angularly each to the other, a flange provided at the terminus of each of said leg portions in coplanar relationship, a clamping sleeve surmounting said leg portions, a clamp bar receivable in said clamping sleeve, a second clamping sleeve provided on said clamp bar, a clamp bar extension receivable in said second clamping sleeve, and a third clamping sleeve provided on said clamp bar extension whereby to frictionally grip an antennae mast, said second clamping sleeve being disposed in a plane normal to the plane of said first-named clamping sleeve, and said third clamping sleeve being disposed in a plane normal to the plane of said second clamping sleeve.
